UNITED STATES PATENT OFFICE.

JOHN F. CARD, OF THREE RIVERS, MICHIGAN, ASSIGNOR TO SHEFFIELD CAR COMPANY,
OF THREE RIVERS, MICHIGAN.

COLLAPSIBLE CORE FOR USE IN THE MANUFACTURE OF COILS.

1,002,367.

specification of Letters Patent.

Patented Sept. 5, 1911.

Application filed May 6, 1911. Serial No. 625,438.

To all whom it may concern:

Be it known that I, JOHN F. CARD, a citizen of the United States, residing at Three Rivers, Michigan, have invented certain new and useful Improvements in Collapsible Cores for Use in the Manufacture of Coils, of which the following is a specification.

This invention relates to improvements in collapsible cores for use in the manufacture of coils.

The main objects of this invention are. First; to provide an improved core for use in the manufacture of coils for electric motors and the like, from flat wire. Second; to provide an improved collapsible coil winding core, which can be readily set up or is quickly knocked-down after the coil has been formed thereon. Third; to provide an improved coil winding core which is adapted for use as an attachment for lathes.

Further objects, and objects relating to structural details, will definitely appear from the detailed description to follow.

I accomplish the objects of my invention by the devices and means described in the following specification.

The invention is clearly defined and pointed out in the claims.

A structure which is a preferred embodiment of my invention is clearly illustrated in the accompanying drawing, forming a part of this specification, in which:

Figure I is a detail side elevation of a structure embodying the features of my invention, the chuck and tail stock of a lathe being shown in conventional form. Fig. II is an enlarged detail section taken on a line corresponding to line 2—2 of Fig. I, the parts being shown with a coil partially mounted thereon. Fig. III is a detail side elevation partially and vertically central section on a line corresponding to line 3—3 of Fig. II. Fig. IV is a transverse section corresponding to that of Fig. II, with the side reaches of the coils hammered down against the sides of the supporting bar 3, that being the last step or operation in forming the coil on the core.

Referring to the drawing, 1 represents the chuck of a lathe and 2 the tail stock.

My improved winding core consists of a supporting bar 3, which is, in the structure illustrated, rectangular in cross section, is provided with longitudinal grooves 4 and

5 in its edges, the bottom of the groove 5 being inclined as illustrated in Fig. III. The bar 1, is provided with a chuck shank at one end and with a bearing 7 at the other. A plurality of disk like core members 8 having hub-like portions 9 on one side and inwardly projecting lugs 10 on their inner edges are provided. The core members 8 are arranged in sets upon the clamping bolts 11 and when clamped together coat to form grooves for the strands of the coil, as 12. The tapered key 13 is arranged in the groove 5 and serves to support the set of core members arranged in that groove. In use the core members are assembled on their clamping bolts and arranged in the supporting bar being suitably retained therein by the coil itself. Additional means for retaining the parts together can be provided if desired.

The wire is fed or delivered to the winding core by any suitable means being preferably held under considerable tension, but as this feed or delivery means forms no part of my present invention I have not illustrated or described the same herein.

The hub-like portions 9 of the core members are preferably of a diameter equal to the thickness of the bar 3. The edges of the core members project beyond the sides 85 of the bar as is clearly illustrated. The wire to be wound is fed into the coil groove formed by the core members as the bar 3 is revolved. I have not attempted to use sufficient tension in winding the coils to cause 90 the side reaches of the coils to lie flat against the sides of the supporting bar.

In practice, after the coil is wound as shown in Fig. II, I press or hammer the sides of the coil down against the sides of 95 the bar as shown in Fig. IV. The material used being ordinarily of soft copper this is easily accomplished. After the sides of the coil have been flattened or pressed against the sides of the supporting bar as 100 shown in Fig. IV, the key 13 is removed. This permits the coil being slipped from the core bar. The clamping bolts 11 are then removed and the core members fall from or may be quickly removed from between the strands of the coil. The coils, when removed from the core ordinarily have a tendency to twist on account of the hardening of the metal, resulting from the bending. In practice I relieve this by an- 110

nealing. By the aid of my improvements I am enabled to produce very rapidly, cores from flat wire which are substantially perfect.

5. I have illustrated and described my improvements in a simple embodiment. I am aware that the improvements are capable of considerable modification in structural details, but as such modification will no doubt 10 be readily understood by those skilled in the art to which this invention relates I have not attempted to illustrate or describe the same herein.

Having thus described my invention, 15 what I claim as new and desire to secure by Letters Patent is:

1. In a device of the class described, the combination of a bar having longitudinal grooves in its edges, the bottom of one of 20 the grooves being inclined, disk like core members having hub-like portions on one side and groove engaging lugs on their inner edges, bolts for clamping said core members together in sets, and a tapered key for 25 said groove having the inclined bottom.

2. In a device of the class described, the combination of a bar having longitudinal grooves in its edges, disk like core members having hub-like portions on one side and 30 groove engaging lugs on their inner edges and bolts for clamping said core members together in sets.

3. In a device of the class described, the combination of a bar having longitudinal 35 grooves in its edges, one of the grooves having an inclined bottom, a plurality of core members having groove engaging lugs at their inner edges, removable clamping bolts for said core members, said core members 40 coacting when assembled to provide grooves for the coil when arranged on said bolts, and a tapered key adapted to coact with the inclined bottom of said groove.

4. In a device of the class described, the 45 combination of a bar having longitudinal grooves in its edges, a plurality of core members having groove engaging lugs at

their inner edges, removable clamping bolts for said core members, said core members coacting when assembled to provide grooves 50 for the coil when arranged on said core.

5. In a device of the class described, the combination of a supporting bar, disk like core members having hub-like portions on one side and removable bolts for clamping 55 said core members together in sets, said core members being spaced by said hub-like portions thereof to receive the strands of a coil therebetween, said sets of core members being removably mounted on said bar. 60

6. In a device of the class described, the combination of a supporting bar, a plurality of core members, and removable clamping bolts for securing said core members together in sets, said core members being adapted to receive the strands of the coil therebetween when arranged on said bolts, there being two sets of said core members mounted on said bar. 65

7. In a device of the class described, the combination of a supporting bar, a plurality of core members, and removable clamping bolts for said core members together in sets, said core members coacting to provide coil 70 grooves when arranged on said bolts, there 75 being two sets of said core members mounted on said bar.

8. In a device of the class described, the combination of a flat supporting bar, core members adapted to be removably mounted 80 on the edges of said bar, said core members being provided with hub-like projections on one side, the diameter of the said projections being substantially the thickness of 85 said bar, the edges of the core members projecting beyond the sides of the bar.

In witness whereof, I have hereunto set my hand and seal in the presence of two witnesses.

JOHN F. CARD. [L. S.]
